UNITED STATES PATENT OFFICE.

HENRY M. SHEER, OF QUINCY, ILLINOIS, ASSIGNOR TO H. M. SHEER COMPANY, OF QUINCY, ILLINOIS, A CORPORATION OF ILLINOIS.

BURNER ATTACHMENT.

Application filed June 10, 1922. Serial No. 567,451.

To all whom it may concern:

Be it known that I, HENRY M. SHEER, a citizen of the United States, residing at Quincy, in the county of Adams and State 5 of Illinois, have invented certain new and useful Improvements in Burner Attachments, of which the following is a specification.

My invention relates to an improvement in 10 Burner Attachments, and the present invention is an improvement on the burner set forth in my application for Letters Patent filed June 15, 1921, Serial No. 477761.

The function of the present invention is to 15 increase the efficiency of the burner, especially when it is desired to carry a large flame.

Normally the flame is held below the 20 spreader-cap, but there are frequent occasions when it becomes necessary to maintain an unusually large flame to meet severe weather conditions.

The present invention permits this increase in flame and produces perfect combustion while having no deleterious effect on the 25 quality of the flame when the same is carried low in the burner proper. Ordinarily to increase the heating flame of the burner, it would be made larger in diameter, or the height of the entire burner would be increased, that is to say by merely extending 30 or lengthening the two perforated screens, together with the outer casing; but the objection to this is the difficulty of securing perfect combustion when carrying a low or 35 medium flame.

My burner as set forth in the above-entitled application with this extension, produces a perfect combustion from a small or 40 low flame up to what would ordinarily be termed a maximum flame, extending slightly past the spreader-cap. Upon attempting to carry a higher flame than this, even by the use of an adjustable air-valve, the flame is very apt to smoke. By the use of this extension, it is possible to increase the flame 45 until it reaches the top of the extension, and still have perfect combustion.

Furthermore, this extension is an article 50 complete in itself, which may be applied to burners already in use without alteration.

In the accompanying drawings:—
The figure is a vertical section through a

burner with my improved extension applied.

A, represents my improved burner fully described in the above-entitled application. 55 B, represents the attachment or extension which is adapted to take the place of the deflector or spreader of the pending application.

This extension B includes a reticulated 60 cylinder 1, a perforated base 2, and an imperforate top 3, all of which are held together in any approved manner, as, for instance, by a central bolt 4 and a nut 5 screwed thereon. The extension B might be variously constructed, and the foregoing is typical, as it is simple and includes few parts, easy to make, and can be made and sold at a moderate price. It is, at the same time, 65 easily applied to burners already in use, and 70 is most effective in accomplishing the functions required of it.

The base is formed with an annular side 6, which fits the upper edge of the inner tube or screen of the burner where the extension 75 or attachment rests conveniently, due to its own weight. By reason of this extension, air is carried and distributed some distance, that is to say, in view of the extension above the burner supporting the combustion of the 80 flame surrounding it to the very top of the extension. When not needed, as is often the case, the extension is removed, and when desired for use, it is a very simple matter to place it on the top of the burner. 85

I claim:

1. A device of the character described including a burner, and an extension composed of a flaring base open at the top and having orifices in the bottom adapted to be supported on the burner, a reticulated cylinder supported on the base, and means for securing the cylinder and base together. 90

2. A device of the character described including a burner and an extension composed of a flaring base open at the top and having orifices in the bottom, adapted to be removably supported on the burner, an imperforate top, a reticulated cylinder between the base and top, and means for clamping said parts 95 of the extension rigidly together. 100

In testimony whereof I affix my signature.

HENRY M. SHEER.
